J. S. BEAN

RAIL JOINT

Filed May 13, 1924

UNITED STATES PATENT OFFICE.

JOSEPH S. BEAN, OF MILL VILLAGE, NEW HAMPSHIRE.

RAIL JOINT.

Application filed May 13, 1924. Serial No. 713,035.

To all whom it may concern:

Be it known that I, JOSEPH S. BEAN, a citizen of the United States, residing at Mill Village, in the county of Sullivan,

5 State of New Hampshire, have invented a new and useful Rail Joint; and I do hereby declare the following to be a full, clear, and exact description of the invention, such as will enable others skilled in the art to which

10 it appertains to make and use the same.

The invention relates to rail joints, and has for its object to provide a device of this character wherein adjacent railroad rails are secured in transverse recesses in the end 15 of a cross tie by means of a wedging member, thereby obviating the use of fish plates and bolts, consequently reducing the cost of upkeep to a minimum.

The tie and rails are preferably formed 20 from a metal, which will not corrode, for instance as aluminum, and will not rapidly become damaged or worn incident to corrosion as is now the main difficulty with metallic ties.

25 A further object is to provide the outer edges of the rail flange with bevelled surfaces and with which bevelled surfaces a tapered key cooperates when driven into one side of the recess in the tie, said tapered 30 key being provided with a flange which overlies the upper side of the adjacent flanges of adjacent rails.

35 A further object is to bevel downwardly and inwardly the inner side of the tread of the rails, thereby presenting a minimum amount of surface with which the flange of a wheel engages and consequently reduces the friction to a minimum.

With the above and other objects in view 40 the invention resides in the combination and arrangement of parts as hereinafter set forth, shown in the drawing, described and claimed, it being understood that changes in the precise embodiment of the invention 45 may be made within the scope of what is claimed without departing from the spirit of the invention.

In the drawing:

Figure 1 is a side elevation of one end of 50 the tie showing the same partly in vertical longitudinal cross section, and a rail disposed therein.

Figure 2 is a top plan view of a tie, showing abutting adjacent rail ends disposed therein.

55

Figure 3 is an end view of the tie, showing adjacent rail ends secured therein.

Referring to the drawing, the numeral 1 designates the cross tie, which is preferably formed from a noncorrosive metal, such for

60 instance as aluminum and 2 the convexed underside thereof, which rests in a road bed, and by being convexed is more positively held by the roadbed. The ends of the tie

1 are provided with transversely disposed 65 recesses 3 having side channels 4 and in which recesses the adjacent ends of rails 5 are received with their flanges 6 within the channels 4. The outer edges of the flanges

6 of the rails are bevelled as shown at 7 70 for engaging the downwardly and outwardly inclined outer wall 8 of the recess 3, and forming a bearing surface for the flange 9 of the angular wedge key 10, which

is adapted to be driven into the inner channel 4 for wedging the adjacent rails 5 outwardly against the inclined surface 8. Thus

it will be seen that the rails at opposite ends of the tie will be positively held in accurate spaced relation, and against spreading. It

75 will also be seen that the use of fish plates or bolts is eliminated, consequently the expense of maintaining track walkers for tightening fish plate bolts is also obviated.

Wedge keys 10 at opposite sides of the 80 track are preferably driven into position in opposed relation, thereby counteracting the tendency of the rails creeping incident to traffic moving over the same.

The invention having been set forth what 90 is claimed as new and useful is:—

A rail joint comprising a railway tie, adjacent abutting rail ends disposed in a recess in the end of said tie, flanges carried

95 by said rails and disposed in channels in the walls of the recess of the tie, the outer edges of said flanges being bevelled, the outer flanges of the rails having their bevelled edges in engagement with a bevelled

100 surface at the outer end of the channel of the recess, an angularly shaped tapered wedge having a narrow and a wide flange, said narrow flange of the wedge engaging a bevelled surface in the other channel and

the bevelled edges of the flanges of the rails at the inner sides of the rails, said wide flange of the angularly shaped wedge overlying the upper sides of the inner flanges of the adjacent rails and the upper wall of the tie recess.

In testimony whereof I have signed my

name to this specification in the presence of two subscribing witnesses.

JOSEPH S. BEAN.
